Primary Examiner — Elizabeth J Oswecki(74) Attorney, Agent, or Firm — JanPaul Guzman, Esq.(57) CLAIM

The ornamental design for a personal Stations of the Cross, as shown and described.

DESCRIPTION

FIG. 1 is a front elevational view of a personal Stations of the Cross showing my new design;

FIG. 2 is a rear elevational view thereof;

FIG. 3 is a left side elevational view thereof;

FIG. 4 is a right side elevational view thereof;

FIG. 5 is a top plan view thereof, the bottom plan view being a mirror image thereof;

FIG. 6 is a front elevational view of a personal Stations of the Cross shown in FIG. 1 in a closed position;

FIG. 7 is a front perspective view of a personal Stations of the Cross shown in FIG. 1 in an open position; and,

FIG. 8 is a rear perspective view thereof.

The broken lines shown in the drawings represent portions of the personal Stations of the Cross that form no part of the claimed design.
